COMBINED WAXING AND CLEANING TOOL

James R. Gilchrist, Derby, and Louis J. Park, Buffalo,
N. Y., assignors to Truly Magic Products, Inc., Buffalo,
N. Y., a corporation of New York

Application May 9, 1955, Serial No. 35,879

Term of patent 14 years

(Cl. D9—2)

Fig. 1 is a perspective view on an enlarged scale of a combined waxing and cleaning tool embodying our new design.

Fig. 2 is a top plan view thereof.

Fig. 3 is a bottom plan view thereof.

Fig. 4 is a side elevational view thereof, the opposite side elevational view being substantially the same.

Fig. 5 is a front elevational view thereof.

Fig. 6 is a rear elevational view thereof on a reduced scale.

I claim:

The ornamental design for a combined waxing and cleaning tool, substantially as shown.
